ATION OF PENNSYLVANIA.

SEATING.

No. 884,736.

Specification of Letters Patent. Patented April 14, 1908.

Application filed January 21, 1897. Serial No. 253,192.

To all whom it may concern:

Be it known that we, JOHN B. KILBURN and EDWARD G. BUDD, both citizens of the United States, and both residing at Philadelphia, in the county of Philadelphia and State of Pennsylvania, have invented a certain new and useful Improvement in Seating, of which the following is a specification.

This invention relates to seating adapted for various uses but of particular utility in railway cars and other vehicles.

The object of the invention is to provide a structure which, in addition to being strong, sufficiently flexible and capable of manufacture at comparatively small cost, is incombustible and is reinforced at points subjected to the greatest strains in order to secure great durability.

In embodying the invention in a detachable cushion such as may be used as a seat- or back-cushion of a car-seat, incombustibility is secured by making the cushion practically wholly of metal. The frame is preferably made of sheet-steel frame sections pressed to the proper form and secured together at their ends and metallic slats may be provided extending across and secured to the frame for the support of the springs over which the covering is drawn. The covering is also of metal, the requisite flexibility being obtained by making the covering of strands of metal woven closely together. These strands are preferably of steel and substantially flat and they are interwoven so closely as to leave no spaces between adjacent strands. If desired, the covering may have a thin coating of incombustible enamel, varnish or other suitable substance applied to its surface. The covering thus prepared is drawn over the spring and secured at its edges to the frame, metallic clamps being preferably used for this purpose. In order to increase the durability of the seating thus constructed, we provide means for reinforcing the seating at such points as, under the ordinary conditions of use, would be apt to show wear first. Thus, we secure adjacent strands crossing each other together at a multiplicity of points distributed over the entire covering so that the several strands will not be forced apart to form openings between them. This is preferably done by applying a drop of such material as molten solder or brazing fluid to the under side of the covering at points apart in both direc-

tions by a small space, for instance, one or two inches. This material is pressed flat while hot and is so applied that it does not show on the exterior of the cushion. In this way one or two strands running in both directions are tied together so that the strength of the covering as a whole is greatly increased and adjacent strands will not be forced apart. Considerable difficulty has been experienced in making the corners of such cushions smooth, due principally to the fold in the covering necessary at this point. In accordance with our invention, we overcome this difficulty by applying a metal filler to each of the corners of the cushion. A thin molten solder or brazing fluid is preferably used for this purpose and may be applied by dipping each of the four corners therein. In this way a smooth clean surface is provided at the corner where the surface is usually rough on account of the fold in the covering and much greater strength is secured at the point where the cushion is most liable to wear, as all the strands at the corner are united, the strands are united to the clamping strip and the latter to the frame. The elasticity of the cushion is in no way decreased, however, as the strengthening coating is confined to the extreme corners.

The preferred embodiment of the invention is illustrated in the accompanying drawings, in which

Figure 1 is an elevation of a cushion partly in section; Fig. 2 is a bottom view of a piece of the covering; Fig. 3 is an enlarged section of the same [—] line 3—3 of Fig. 2; Fig. 4 is a horizontal section through a corner of the cushion; and Fig. 5 is a perspective view of one of the corners.

Referring to these drawings, the frame of the cushion consists of four sheet-metal frame sections secured together at their ends and each pressed to provide a body portion 1, an inwardly curled flange 2 at the top thereof, and an inwardly extending flange 3 at the bottom, curled at its edge as indicated at 4. Extending across between the side members of the frame are a plurality of metallic slats 5, the ends of which are secured to the flanges 3. These slats support spiral springs 6 arranged in lines, and each line of springs 6 supports a flat metallic spring 7, the ends of which are downwardly turned and may be secured to the body portions 1 of the side members of the frame. The springs 6 and 7

may be of such size that the covering of the cushion is given the desired curvature, and for this purpose metallic forming-pieces may be secured to the end members of the frame.

5 The covering material of the cushion consists of substantially flat metallic strands, preferably steel, closely interwoven in the manner indicated in Fig. 2. These strands may be of rectangular cross-section, but preferably the upper face of each strip is somewhat convex. The strands are woven so closely together that there are practically no spaces between adjacent strands. If desired, a coating may be applied to the covering, such as a thin incombustible enamel or varnish. In order to strengthen the covering as a whole and prevent the several strands from raveling, we provide means for tying together adjacent strands and strands 10 crossing each other, at a great number of points distributed over the entire covering. This is preferably done by applying thin molten solder or brazing material to the under side of the covering at points an inch or 15 two inches apart in both directions over the entire under side of the covering. This material is pressed flat while it is hardening, and when it is hard it binds together a number of the strands of the covering, as indicated at 8 Figs. 2 and 3. This material does not show on the upper surface of the cushion, as it does not run through the covering, but it 20 fills the shallow depressions on the under side of the covering formed by the weaving of the strands and holds these strands together so tightly that they will not be separated under any of the usual strains to which the cushion is subjected. The covering thus constructed is applied to the cushion in the usual manner, its edges being drawn down over the members of the frame and carried under the flanges 3 and around the curled edges 4 thereof. Metallic clamping strips 9 are gripped around the curled portions 4 to hold 25 the covering to the flanges 3 securely in the usual manner. On account of the folds in the covering necessary at the corners of the cushion, it has been impossible heretofore to make the corners as smooth and of as neat 30 appearance as has been desired.

We effect a great improvement in the appearance of the cushion, and also strengthen the construction materially, by applying a metallic coating to each of the corners of the cushion, which fills the depressions formed by the folds in the covering, binds the strands of the covering together so as to prevent raveling and unites the parts of the covering, the frame and the clamping strip 35 so as to form practically a unitary structure. This is preferably done by dipping each corner of the cushion in a bath of thin molten solder or brazing fluid. This material adheres to the surface of the cushion, fills in the 40 many shallow depressions, and when hard

50 presents a smooth and finished surface. Thus, in Fig. 4, which is a horizontal section through a corner of the cushion, we have shown the fold in the covering necessary at this point and it will be seen that this fold forms a depression in the surface of the cushion at the point 10 such that a projecting part might catch upon the fold in the covering and either tear it or pull it from the frame. By applying the coating as above 55 described, this depression is completely filled, as shown in Fig. 4, as well as any others upon the surface of the cushion, the coating 11 serving to smooth over all such spots which otherwise would appear rough. Additionally, this coating unites the several strands of the covering and unites the covering and clamping strip 9, as indicated at 12, Fig. 1, thus contributing greatly to the strength of the cushion. In Fig. 5, a perspective view 60 of one corner of the cushion is shown, from which it will be seen that the coating 11 smooths the surface of the corner of the cushion so that a much more attractive appearance is presented.

Having now described our invention, what we claim as new therein and desire to secure by Letters Patent is as follows:—

1. In seating, the combination of a metallic frame and a flexible, incombustible covering secured thereon, consisting of metallic strands closely interwoven, and a plurality of bodies of metal distributed over said covering, each securing a plurality of strands running in one direction together and to one or more strands crossing the same, substantially as set forth.

2. In seating, the combination of a metallic frame and a flexible, incombustible covering secured thereon, consisting of metallic strands closely interwoven and a plurality of bodies of metal distributed over the under side of said covering, each securing a plurality of strands together and to a plurality of strands crossing the same, substantially as set forth.

3. In seating, the combination of a metallic frame and a flexible, incombustible covering secured thereon, consisting of metallic strands closely interwoven and a plurality of drops of a soldering compound distributed over the under side of the covering, each securing a plurality of strands together and to a plurality of strands crossing the same, substantially as set forth.

4. In seating, the combination of a metallic frame, a flexible incombustible covering consisting of woven metallic strands extending over said frame and covering the sides thereof, said covering being secured at its edges to the frame, and a filling of metal applied to the covering while reduced by heat for providing a smooth surface at the corners of the frame, substantially as set forth.

5. In seating, the combination of a metal-

- lic frame and a flexible incombustible covering consisting of woven metallic strands extending over said frame and along the sides thereof and secured at its edges to the frame, 5 said covering having a fold therein at the corner of the frame, and a filling of metal applied to the covering while reduced by heat for providing a smooth surface over said fold, substantially as set forth.
- 10 6. In seating, the combination of a metallic frame, a flexible incombustible covering consisting of woven metallic strands extending over said frame and covering the sides thereof, said covering being secured at its 15 edges to the frame, and means for uniting the strands of the covering at the corners of the frame by a filling of metal applied thereto while reduced by heat, substantially as set forth.
- 20 7. In seating, the combination of a metallic frame, a flexible incombustible covering consisting of woven metallic strands extending over said frame and covering the sides thereof, a clamping member securing the 25 edges of the covering to the frame at the bottom thereof, and a filling of metal applied to the covering while reduced by heat, said filling serving to unite the covering and frame and smoothing the surface of the seating, 30 substantially as set forth.
8. In seating, the combination of a metallic frame, a flexible incombustible covering consisting of woven metallic strands extend-
- ing over said frame and covering the sides thereof, a clamping member securing the 35 edge of the covering to the frame at the bottom thereof, and a filling of metal applied to the covering while reduced by heat and serving to unite the covering and said member and smooth the surface of the cushion, substantially as set forth.
9. In seating, the combination of a metallic frame, a flexible incombustible covering consisting of woven metallic strands extending over said frame and covering the sides 45 thereof, and a metallic coating on said covering at the corners of the frame smoothing the surface thereof, substantially as set forth.
10. In seating, the combination of a metallic frame, a flexible incombustible covering consisting of woven metallic strands extending over said frame and covering the sides thereof, means for securing the edges of the covering to the frame at the bottom thereof, and a metallic coating smoothing the 50 surface of said covering at the corners of the frame and uniting the covering to said securing means, substantially as set forth.

This specification signed and witnessed this 17th day of January, 1907.
